UNITED STATES PATENT OFFICE.

CHARLES H. FOSTER, OF OMAHA, NEBRASKA.

HOT-AIR REGISTER.

SPECIFICATION forming part of Letters Patent No. 773,068, dated October 25, 1904.

Application filed June 1, 1903. Serial No. 159,399. (No model.)

To all whom it may concern:

Be it known that I, CHARLES H. FOSTER, a citizen of the United States, residing at the city of Omaha, county of Douglas, State of Nebraska, have invented a certain new and useful Hot-Air Register, of which the following is such a full, clear, and exact description as will enable any one skilled in the art to which it appertains to make and use the same, reference being had to the accompanying drawings, forming part of this specification.

My invention relates to hot-air registers, and more particularly to that class of registers known as "side-wall" registers, which are placed in a substantially vertical position in the wall of a room in place of in the floor.

My invention consists in part in the combination, with a frame provided with a valve-opening, of a valve having one end pivoted adjacent to the top of said opening, a slidingly-mounted grille, and connections between said grille and valve for moving the latter.

My invention also consists in various other novel features and details of construction, all of which will be described in the following specification and pointed out in the claims affixed hereto.

In the accompanying drawings, which illustrate one form of register made in accordance with my invention, Figure 1 is a front elevation. Fig. 2 is a section on the line 2 2 of Fig. 4. Fig. 3 is a section through the frame, taken on the line 3 3 of Fig. 4. Fig. 4 is a vertical central section on the line 4 4 of Fig. 1. Fig. 5 is also a vertical central section, but showing the register in position in the wall. Fig. 6 is a rear view of a portion of the register, and Fig. 7 is an isometric projection of a portion of the grille.

Like marks of reference refer to similar parts in the several views of the drawings.

10 is the frame or border of the register. This frame or border 10 is adapted to rest against the base-board 11.

The reference character 12 designates the plaster, and 13 the lathing of the wall. Formed in the frame or border 10 is a valve-opening 14. Projecting rearwardly from the frame or border 10 are two vertical flanges 15

and a cross-flange 16. The vertical flanges 15 are at right angles to the frame or border, while the cross-flange 16, extending across the top of the register, is preferably somewhat inclined, as best shown in Figs. 4 and 5. 55 The lower end of the frame or border 10 projects some distance from the wall, as best shown in Fig. 5. Formed on the flanges 15 and extending into the opening 14 are ribs 17 and 18, each of said ribs being preferably 60 composed of a plurality of sections. The rear edges of these ribs 17 and 18 form shoulders against which the valve 19 is adapted to rest when the valve is in its closed position. The upper end of the valve 19 is bent around a 65 wire or rod 20. This wire or rod 20 rests upon the upper ends of the ribs 17 and 18. At the central portion of the flange 16 is formed a downwardly-projecting lug 21, in which is formed a notch adapted to receive the upper 70 coiled end of the valve 19. The valve is prevented from coming out of the front of the valve-opening by means of downwardly-projecting rib 22. This rib 22 has a central cut-away portion 23 for convenience in casting the border. 75 The valve 19 is preferably provided with a slot 24 for the reception of the corner of the lug 21 when the valve is in its open position, as shown in Fig. 5. The reference character 26 designates the grille, which is composed 80 of two sets of bars or rods crossing each other and arranged in different planes. These two sets of bars or rods are connected and preferably formed integral. The grille 26 is provided with two knuckles 27, by means of which it 85 is detachably pivoted to the valve 19. Arranged adjacent to the lower end of the grille 26 is an auxiliary grille 28, which is either rigidly secured to or formed integral with the frame or border 10. This auxiliary grille 90 28 is provided with detents 29, adapted to engage with teeth 30, formed on the lower end of the grille 26 in order to maintain the grille in its raised position. The grille 26 is also provided with a forwardly-projecting portion 95 31, which serves as a handle for raising and lowering the grille. The upper end of the grille 26 is provided at each side with a projection 32, which projections are adapted to pass through openings 33 in the ribs 17 and 100

18 hereinbefore described. Below these openings 33 the said ribs are provided with inclined portions 34, upon which the said projections 32 rest when the valve is in its closed position. These projections when thus resting upon the inclined portions 34 act as trunnions and enable the weight of the grille 26 to hold the valve 19 firmly against the ribs 17 and 18, as shown in Fig. 4. The rib 17 is provided with an offset portion 35, as shown in Fig. 5. This offset portion 35 is adapted to coöperate with a lug 36, so as to normally prevent the lower end of the said grille from being swung out of the valve-opening 14. The reference character 38 designates the flue-pipe, which is provided with flanges 39, forming the flue-opening and surrounding the flanges 15 and 16 of the valve-opening. In order to guide these flanges 39 into position and to hold them close to the flanges 15 and 16 hereinbefore described, I provide the frame or border 10 with a number of guide-lugs 40. Each of these guide-lugs is provided with an inclined V-shaped face 41, which is directed toward the flange on the border 10. When the grille 26 is in its lowest position, as shown in Fig. 4, the valve 19 will be held firmly against the shoulders formed by the rear edges of the ribs 17 and 18, and thus completely and effectively close the valve-opening 14. When, however, it is desired to open the valve 19, the grille 26 is raised by means of the handle 31, so as to cause the teeth 30 on the lower side of the grille to engage with the detents 29 on the upper end of the auxiliary grille 28. This will swing the valve 19 out into the flue-pipe 38. By continuing the upward movement of the grille 26 the valve 19 can be swung completely across the pipe, as shown in Fig. 5. By the engagement of the lug 36 with the offset 35 of the rib 17 the grille is normally kept from swinging out of the valve-opening. When, however, it is desired to detach the grille 26, the said grille is forced toward the left-hand side of the opening. This is permitted by means of the resiliency of the valve 19, which is preferably formed of sheet-steel. As soon as lug 36 is disengaged from the rib 17 the grille can be swung forward and upward. The form of the knuckles 27 is such that when this is done they become detached from the valve 19. The valve 19 can also be detached from the border or frame by forcing the central part of its upper end downwardly, so as to disengage it from the lug 21. By forming the grille of two sets of bars or rods arranged in different planes I secure a greater amount of opening in the grille, and thus am enabled to discharge the full volume of air from the flue-pipe 38.

Having fully described my invention, what I claim as new, and desire to secure by Letters Patent of the United States, is—

65 1. In a hot-air register or the like, the com-

bination with a frame provided with a valve-opening, of a valve having one end pivoted adjacent to the top of said opening and arranged to swing inwardly, a grille mounted in said opening to move substantially in the plane thereof, and connections between said grille and valve for moving the latter.

2. In a hot-air register or the like, the combination with a frame provided with a valve-opening, of a valve having one end pivoted adjacent to the top of said opening and arranged to swing inwardly, and a grille pivotally connected to said valve for moving the same, said grille being movable substantially in the plane of said opening.

3. In a hot-air register or the like, the combination with a frame provided with a valve-opening, of a pivoted valve for said opening, a grille mounted in said opening to move substantially in the plane thereof, a lug carried by said grille and engaging with said frame to normally hold said grille against movement out of said opening, and hooks connecting said grille and valve.

4. In a hot-air register or the like, the combination with a frame provided with a valve-opening, of a pivoted valve in said opening, a grille mounted in said opening to move substantially in the plane thereof, a lug carried by said grille and adapted to be sprung into engagement with said frame by the resiliency of said valve, and hooks connecting said grille and valve.

5. In a hot-air register or the like, the combination with a frame provided with a valve-opening, of a pivoted valve for said opening, a main sliding grille, connections between said main grille and valve for operating the latter, and an auxiliary grille adjacent to said main grille.

6. In a hot-air register or the like, the combination with a frame provided with a valve-opening, of a valve having one end pivoted adjacent to the top of said opening, a main sliding grille, connections between said grille and valve for operating the latter, and an auxiliary grille adjacent to the lower end of said main grille for closing the opening between said frame and main grille when the latter is moved.

7. In a hot-air register or the like, the combination with a frame provided with a valve-opening, of a valve having one end pivoted adjacent to the top of said opening, a main sliding grille, connections between said grille and valve for operating the latter, an auxiliary grille adjacent to the lower end of said main grille, and teeth carried by one of said grilles for engaging with the other to hold said main grille in position.

8. In a hot-air register or the like, the combination with a frame provided with a valve-opening, of a valve having one end pivoted adjacent to the top of said opening, a main sliding grille, connections between said grille

and valve for operating the latter, an auxiliary grille adjacent to the lower end of said main grille, and teeth carried by said main grille for engaging with said auxiliary grille to hold the former in position.

9. In a hot-air register or the like, the combination with a frame provided with a valve-opening, of a pivoted valve, a grille, connections between said grille and valve, shoulders on the frame at the sides of said opening provided with bearings, and trunnions carried by said grille and coöperating with said bearings and connections to hold said valve firmly against said shoulders when said valve is in its closed position.

10. In a hot-air register or the like, the combination with a frame provided with a valve-opening, of a pivoted valve, a grille, hooks connecting said grille and valve, shoulders on the frame at the sides of said opening provided with bearings, and trunnions carried by said grille and coöperating with said bearings and hooks to hold said valve firmly against said shoulders when said valve is in its closed position.

11. In a hot-air register or the like, the combination with a frame provided with a valve-opening, of a sliding grille for operating said valve, shoulders on the frame at the sides of said opening against which said valve is adapted to rest, an offset in one of said shoulders, and a lug carried by said grille and engaging with said offset to normally prevent said grille from swinging out of said opening.

12. In a hot-air register or the like, the combination with a frame provided with an opening, of a grille for said opening, said grille consisting of two connected sets of bars or

rods, said sets crossing each other and lying in different planes.

13. In a hot-air register or the like, the combination with a frame provided with an opening, of a grille for said opening, said grille consisting of two integral sets of rods or bars, said sets crossing each other and lying in different planes.

14. In a hot-air register or the like, the combination with a frame having an opening, of a flange adjacent to said opening, and one or more guide-lugs adjacent to said flange, said lug or lugs being each provided with a V-shaped inclined edge.

15. In a hot-air register or the like, the combination with a frame provided with a valve-opening, of a valve having a resilient edge, and means for supporting the ends of said edge, said frame having a recess intermediate of said supports, into which recess said edge is sprung to retain it in pivotal position on the supports.

16. In a hot-air register or the like, the combination with a frame provided with a valve-opening, of a valve of resilient material having a reinforced edge, and means for supporting the ends of said edge, said frame having a recess intermediate of said supports, into which recess said edge is sprung to retain it in pivotal position on the supports.

In testimony whereof I have hereunto set my hand and affixed my seal in the presence of the two subscribing witnesses.
